DOUBLE-ACTING WRENCH FOR FLANGES

Daniel Baeza, Brooklyn, N. Y.

Application August 18, 1944, Serial No. 550,049

2 Claims. (Cl. 81—55)

1

This invention relates to new and useful improvements in a double acting wrench for flanges.

The invention proposes a new and improved double acting wrench which is characterized by a jaw shaped member having top and bottom arms connected with a vertical back. It is proposed to mount a bottom socket upon the bottom one of said arms for engaging one end of a bolt and nut of a flange. It is proposed to provide a top socket for engaging the other end of said bolt and nut, and it is proposed to slidably and turnably mount a stem of said top socket through said top arm. It is furthermore proposed to provide a pressure arm slidably mounted on said vertical back for engaging said top socket for urging same downwards. It is contemplated to use a spring coaxially on said vertical back for urging said pressure arm and said bottom arm resiliently towards each other.

The invention also contemplates a modified form provided with means for locking said pressure arm in various positions on said vertical back.

Still further, the invention proposes the construction of a double acting wrench for flanges which is simple and durable and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a double acting wrench constructed in accordance with this invention, and shown engaged upon flanges.

Fig. 2 is a plan view of Fig. 1.

Fig. 3 is a horizontal sectional view taken on the line 3—3 of Fig. 1.

Fig. 4 is an enlarged fragmentary sectional view taken on the line 4—4 of Fig. 1.

Fig. 5 is a side elevational view of a double acting wrench for flanges constructed in accordance with a modified form of this invention and shown applied to a pair of flanges.

Fig. 6 is a fragmentary enlarged sectional view of a portion of Fig. 5.

The double acting wrench for flanges in accordance with the form of the invention disclosed in Figs. 1 to 3, includes a jaw shaped member having a top arm 10, a bottom arm 11, and a vertical back 12 rigidly connected between and connecting said arms. The vertical back 12

2

is in the nature of a rod. The top and bottom arms 10 and 11, respectively, are in the nature of rigid metal strips. A bottom socket 13 for engaging the bottom end of a bolt or nut 14 engaged through the flange 15, is fixedly mounted on said bottom arm 11. This bottom socket 13 is formed with inwardly projecting lugs 13a to prevent the bolt or nut 14 from falling out of the socket 13. A top socket 16 engages the other end of said bolt or nut 14, and is connected with a stem 17 which is slidably and turnably mounted through said top arm 10. The stem 17 has a top head 18 which may be a ratchet arrangement through which a small handle or rod 19 engages, by which the socket 16 may be turned. A pressure arm 20 is slidably mounted on said vertical back 12. A spring 22 coaxial on the vertical arm 12 urges said pressure arm 20 upwards. This spring 22 acts between the pressure arm 20 and the top arm 10. The spring 22 also urges the vertical back 12 upwards, and so indirectly urges the bottom arm 11 upwards. The top socket 16 is removably held upon the stem 17 with a spring-pressed locking ball 23.

25 The operation of the double acting wrench is as follows:

The handle 19 may be gripped and turned for screwing down or screwing up, the nut, or the bolt of the bolt and nut 14. When the handle 30 19 is turned in one direction, the jaw shaped member consisting of the top and bottom arms 10 and 11, and the vertical back 12, will be swung in one direction across the edges of the flanges 15. The handle 19 will now transmit rotations 35 to turn the nut while the socket 13 holds the bolt for turning.

When it is desired to remove the double acting wrench, it is merely necessary that the handle 19 be lifted upwards so as to raise the pressure 40 arm 20, by compressing the spring 22. The bottom socket 13 may now be removed from the bottom end of the bolt and nut 14.

In Figs. 5 and 6 a modified form of the invention has been disclosed which is similar to the prior form distinguishing merely in the fact that means is provided for locking said pressure arm 20 in various positions on said vertical back 12. More specifically, the pressure arm 20 is provided with a boss 25 at its back end, through which the vertical back 12 freely passes. A bushing 26 is threadedly mounted in the bottom of the boss 25, coaxially of said vertical back 12. This bushing 26 has a tapered upper end 27 which is formed with slits 28 and which engages a complementary taper in said boss 25. When the bushing 26 is

turned in one direction the taper 27 will be disengaged from the complementary taper of the boss 25. When the bushing 26 is turned in the other direction the taper 27 will be forced against the taper in the boss 25. Because of said slots 28 the top portion of said bushing 26 will be contacted and will grip the vertical back 12.

Another variation, in this form of the invention, resides in the arrangement of the bottom socket 13'. This socket 13' has a coaxial bottom threaded portion 29. The bottom arm 11 has an upturned hexagonal end 30 upon which the hexagonal opening 29 has been engaged. The top socket 16 is removably held upon the stem 17 with a spring-pressed locking ball.

The operation of this form of the invention is the same as the prior form, distinguishing merely in the fact that the sockets 16 and 13' are exchangeable for other sockets, to adapt the double acting wrench for bolts and nuts of different sizes. Moreover, the pressure arm 20 may be locked in various positions upon said vertical back 12 so as to lock the pressure arm 20 in selected positions in relation to the bottom arm 11. This will prevent any possibility of the wrench slipping off the bolt and nut during the operation of tightening or loosening same.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A double acting wrench for flanges, comprising a jaw-shaped member having top and bottom arms connected with a vertical back, a bottom socket for engaging one end of a bolt or nut of a flange and fixedly mounted on said bottom arm, a top socket for engaging the other end of said bolt or nut and slidably and turnably mounted through said top arm, a pressure arm

slidably mounted on said vertical back and engaging said top socket for urging said top socket downwards, a spring coaxially mounted on said vertical back and urging said pressure arm and said bottom arm towards each other, and means for locking said pressure arm in various positions on said vertical back, and including a bushing threadedly mounted upon said pressure arm coaxially of said rod and having a tapered portion engaging a complementary tapered portion on said pressure arm.

2. A double acting wrench for flanges, comprising a jaw-shaped member having top and bottom arms connected with a vertical back, a bottom socket for engaging one end of a bolt or nut of a flange and fixedly mounted on said bottom arm, a top socket for engaging the other end of said bolt or nut and slidably and turnably mounted through said top arm, a pressure arm slidably mounted on said vertical back and engaging said top socket for urging said top socket downwards, a spring coaxially mounted on said vertical back and urging said pressure arm and said bottom arm towards each other and including a bushing threadedly mounted upon said pressure arm coaxially of said rod and having a tapered portion engaging a complementary tapered portion on said pressure arm, said top socket having a stem engaging through said top arm and provided with a head by which it may be turned.

DANIEL BAEZA.
